REMOTELY CONTROLLED REGISTER
SYSTEM

Clyde Smith, Hopkinsville, Ky.

Application August 7, 1939, Serial No. 288,702

10 Claims. (Cl. 312—56)

The invention pertains to remotely controlled register systems and particularly to registers and systems in which balls are released by remote control and the registers then operate to effect counting and registration of the released balls.

The objects of the invention are to release, simultaneously, or in rapid succession and at irregular intervals, in a register office balls, preferably all of the same size, having variant significances and variant values, to assemble at one register all balls having similar significance although of variant values, to operate a register device at such a point to indicate total value of all balls of that significance, then to assemble all registered balls from all such points to operate a grand totalizer to indicate total value of all balls of all significances, and to render such indication at repeated occasions without interrupting the above noted release of balls. A further object is to release by one act a plurality of balls of variant significances.

These objects are accomplished by providing at sales windows ticket issuing devices having electrical contacts which are operated concomitantly with the issuance of a ticket, by providing at a registry office electrically operable ball emitters connected by circuits to the ticket issuing device contacts to be controlled thereby, by providing ducts or ball passage ways, by providing a ball retaining device and a ball counting register at a point where ducts of similar significance unite, by providing further ducts from the registers to a further ball concentration point and by providing a further ball counting register for indicating a grand total of all balls at the further ball concentration point. In one feature of the invention, a single act releases a plurality of balls of variant significances, which by the described ducts are guided to separate and independent ball-counting registers.

A further object of the invention is to provide a ball counter in which each ball is registered by translation of a predetermined quantity of fluid and in which numerical registration is effected by a fluid motor propelled by the translated fluid.

In the drawings:

Figures 1 and 2 taken together show a general circuit and duct arrangement including seven substation ticket issuing devices each illustrated in mechanical detail in a further similar device in Fig. 6;

Figure 3 shows elevation of a ball counter;

Figure 4 shows side elevation of the ball counter;

Figure 5 shows motor and spring;

Figure 6 shows details of a further ticket issuing device;

Figure 7 shows a detail of Figure 6 in operated condition; and

Figures 8 and 9 show vertical sectional view and horizontal section of an electromagnetically controlled ball emitter.

Like reference numerals indicate like parts in the several views. Numerals 1 to 25 inclusive and numeral 50 are descriptive. A plus sign indicates a grounded battery.

Description of apparatus

Referring to Figures 3 and 4 illustrating the ball counter: a frame 30 supports a fixed shaft 32, a rotary power shaft 33, a counting pump block 34, an oil supply tank 35, a fluid motor 36, and a numerical register 37. Counting pump block 34 comprises three internal cavities 29, 38, 39, connected by piping to intake manifold 40 through individual check valves 41 and connected to output manifold 42 through check valves 43, 44 leading to fluid motor 36 driving register 37. A waste pipe 45 extends from motor 36 to tank 35.

Shaft 33 carries a ball drum 50, which has peripheral rows of ball pockets 51 for \$2 balls, 52 for \$5 balls, 53 for \$10 balls, 54 for \$25 balls, and 55 for \$50 balls, there being fewer pockets per row for \$25 and \$50 balls. Balls 56 are fed to drum 50 from a hopper 57.

Shaft 32 supports pivotally five cam followers 61 for \$2 balls, also one each for 62 for \$5 balls, 63 for \$10 balls, 64 for \$25 balls, and 65 for \$50 balls. Adjustments for the cam followers severally are indicated at 66. Cams 64 and 65 have longer cam edges, providing a longer time period than 61, 62, 63 for flow of a greater quantity of fluid yet not increasing speed of fluid flow proportionately.

Plungers 71, 72, 73, 74, 75 project into cavities 29, 38 and 39 and are drawn by springs attached to the frame to hold the plungers against their respective cam followers. Cavities 38 and 39, manifolds 40 and 42, and motor 36 normally are filled with oil, a further supply of oil being provided at 77 in tank 35.

The ticket vending machine shown in Figures 1, 6 and 7 is fully described and illustrated in United States Patent No. 2,034,904, issued to O. Hoyer. To the Hoyer machine are added for purposes of embodying this invention electrical contacts 81 and 82, and a mechanical stop 83. Contact 81 is held open by mechanical engagement of member 84 carried by slide 85 when slide

85 is in normal position as shown. Stop dog 83 engages stop lug 86 on lock-arm 87 should slide 85 be operated and lock-arm 87 unoperated, but should lock-arm 87 be operated as shown in Figure 7 the stop dog 83 then may pass. Stop lug 88 on lock-arm 87 engages stop dog 89 to lock slide 85 against operation should lock-arm 87 be operated before slide 85 has been moved from normal. Lock-arm 87 is operated by magnet 90 as explained in the Hoyer patent.

A constantly rotating gear wheel 91 is mounted upon the outside of the body frame of the ticket issuing machine coaxially with the lid hinges 92. A friction roller 93 is journaled upon the lid of the machine; it extends across all ticket issuing apertures, and is geared to the wheel 91, being thus constantly rotated. Opposite each ticket aperture are pivoted feeler arms 94, each of which controls a contact 82 normally open. Opposite each ticket aperture are fixed guide springs 95. A ticket 96 when issued by a slide 85 is guided by a spring 95 into engagement with follower means power roller 93; it is carried by the roller under arm 94, operating the arm to close the contact 82 (as shown), which is individual to the operated slide 85.

A ball emitter 100 is shown in Figures 8 and 9, Figure 8 being a vertical section on line 8-8 of Figure 9, and Figure 9 being a horizontal section on line 9-9 of Figure 8. Tube 101 is supplied with balls from a magazine (not shown), and tube 102 guides an emitted ball to a predetermined point. Solenoid 103 is marginal in operation, closing the contact points 104 when partly energized, and operating to emit a ball 105 only when fully energized. Contacts 106 normally are held closed by a feeler 107 pivoted at 108 only when a ball 105 is in position to be emitted, as shown. Mechanical springs 109 serve to retain ball 105 in position but yield when plunger 110 of solenoid 103 is operated. Ball drum 50 and shaft 33 (Figs. 3 and 4) are driven by gear 111 (Fig. 5), pinion 112 and motor 113 acting through a yielding connection 114. Mechanical details illustrated in the emitter 100 of Figs. 8 and 9 are present in the further emitters 100-A to 100-R in Fig. 2.

Substations, or ticket windows, 121 to 127, inclusive (Fig. 1), each of which consists of a Hoyer ticket machine modified according to Figures 6 and 7, are connected by conductors in a cable 128 to central office ball emitting apparatus 100-A to 100-R, inclusive, each of which is a ball emitter (Figs. 8 and 9). Complete ball counters according to Figures 3 and 4 are indicated at 131 to 139, inclusive (Fig. 2), only the ball drums and numerical registers being shown.

In an adaptation of this invention to horse race betting, horse No. 1 is represented by emitters 100-A to 100-F, 100-M, 100-P, which are connected by ducts 141, 142, 143, 144, 145 to counter 131 for horse No. 1. Similarly, horse No. 2 is represented by emitters 100-G to 100-L, 100-N, 100-Q which are connected by ducts 146, 147, 148, 149, 150 to counter 132 for horse No. 2. Further ducts 151 extend from counters 131 and 132 to a grand totalizer 133. Positioned near the ducts 143, 144, 148, 149 and operable to be positioned in the ducts to obstruct movement of balls, are stop gates 155 on a shaft 156 tensioned by spring 157 and restrained by latch 158 which may be unlatched by movement of armature 159 of magnet 160 under control of contacts in program clock 161. Gates 155 may be reset by operation of a handle, 162. Contacts

163 controlled by rotation of shaft 156 when released by latch 158 may energize an alarm device to signal in attendant.

Operation of the system is as follows:

To issue a \$2 ticket on horse No. 1, an attendant at substation 121 operates slide 85, Fig. 6, to engage stops 83 and 85, thus closing upper contacts 81 at substation 121, Fig. 1, thus closing a circuit including contact 81 at substation 121, resistor 170, conductor 171, solenoid 103, of emitter 100-A, and grounded battery. Marginal current because of resistor 170 energizes the solenoid 103 to close the contact 104 of emitter 100-A, thus closing a circuit including contacts 104 and 106 of emitter 100-A, conductor 175, magnet 90 at substation 121, and grounded battery. Magnet 90 at substation 121 is energized and armature member 87 accordingly is operated, engaging all stops, 88, 89, on all slides not moved at substation 121 and disengaging the stops 83 and 86 of the moved slide. Had no ball been in position to be emitted, the last described circuit would not have been formed and no further action would be possible until a ball moves into position to be emitted. The attendant now completes the movement of the slide 85 and shifts a ticket to the roller 93, where the ticket operates the arm 94 and closes contact 82, shunting the resistor 170 and increasing the current in the first described circuit to energize solenoid 103 of emitter 100-A fully. The plunger of the solenoid emits the positioned ball into one of the ducts 141, releasing the feeler 107, Fig. 8, and opening the contact 106 of emitter 100-A, thus deenergizing magnet 90 at substation 121 and unlocking all ticket slides at substation 121.

In like manner, operation of a different slide at \$2 substation 121 to close lower contact 81 will close a circuit over conductor 181 to ball emitter 100-G and will emit a \$2 ball into one of the ducts 146 pertaining to horse No. 2.

Similarly, operation to close the upper contact 81 at substation 122 will result in currents in conductors 182 and 183 to emit a \$2 ball into one of the ducts 141 pertaining to horse No. 1, while operation to close the lower contact 81 at substation 122 will result in currents in conductors 184 and 183 to emit a \$2 ball into one of the ducts 146 pertaining to horse No. 2.

Likewise, contacts in \$5 substation 123 control \$5 balls emitted from emitters 100-C and 100-I by currents in conductors 185, 186, 187. Contacts in \$10 substation 124 control balls emitted from emitters 100-D and 100-J by currents in conductors 188, 189, 190. Contacts in \$25 substation 125 control balls emitted from emitters E and K by current in conductors 191, 192, 193. Contacts in \$50 substation 126 control balls emitted from emitters 100-F and 100-L by currents in conductors 194, 195, 196.

Issuance of a single ticket at combination \$6 substation 127 places three bets upon one horse, a bet of the first class requiring a registering \$2 ball in first class counters, as 131, 133, also a bet of the second class requiring a \$2 ball in second class counters, as 134, 136, and a bet of the third class requiring a \$2 ball in third class counters, as 137, 139.

To attain this result, upper contact 81 at substation 127 closes a circuit which includes resistor 201 and conductor 202 to a junction point where it branches through three solenoids, 103 in emitters 100-M, 100-N, and 100-O to grounded battery, energizing the three solenoids

marginally and closing the three contacts, 104, by which the response circuit is formed, including contacts 104, 106, conductor 212, magnet 90 at substation 127, and grounded battery. Magnet 90 then permits issuance of a ticket to close contact 82, producing full energization of sole-noids 103, and resulting in emitting three \$2 balls into ducts 142, 214, 215 which lead to the counters 131, 134, 137.

Similarly, operation of lower contact 81 at substation 127 will operate emitters 100—P, 100—Q, and 100—R, by currents in conductors 216 and 212, and will result in emitting three \$2 balls into ducts 147, 217, 218, which lead to counters 132, 134, 137.

Apparatuses 221 and 222 (Fig. 2) indicate two complete equipments like apparatus 220.

Emitted balls from emitters 100—A to 100—F inclusive and 100—M for bets of the first class on horse No. 1 are guided by ducts 141, 142, 143, 144, 145 (Figs. 1 and 2) to hoppers, as 57 (Figs. 2 and 4), whence they enter pockets, 51 to 55, in ball drum 50 (Fig. 4). As each \$2 ball is carried by the drum under its cam 61 it lifts the cam and forces a plunger 71 into cavity 38 displacing a quantity of fluid equal to 2 predetermined volume units through valve 43 into output manifold 42 and through fluid motor 36 into supply tank 35. The fluid motor 36 operates the register 37 to indicate "2." When the ball thus tallied disengages from the cam 61 the springs 76 draw the plunger 71 down into the normal position shown, thus drawing into cavity 38 through intake valve 41 a quantity of fluid to replace the expelled fluid.

A plurality of balls, five or fewer, may occupy pockets 51 (5 shown) and may operate a like number of plungers 71 simultaneously in a single cavity 38 through a single intake valve 41 and a single output valve 43. A \$5 ball will be directed by ducts to pocket 52 in drum 50 and will operate cam 62 to operate plunger 72, which may have an axial travel and a plunger cross area to force a quantity of fluid equal to five volume units through valve 43 into output manifold 42 and through fluid motor 36, which operates the register 37 to increase its prior indication by 5.

Similarly a \$10 ball in pocket 53 operates cam 63 and plunger 73 to displace 10 volume units of fluid through motor 36; a \$25 ball in pocket 54 operates cam 64 and plunger 74 to displace 25 volume units of fluid through motor 36; and a \$50 ball in pocket 55 operates cam 65 and plunger 75 to displace 50 volume units of fluid through motor 36.

Plungers which displace the larger quantities of fluid are operated more slowly, as provided for by the longer cam face on cam 64 (Fig. 4) and by the greater distance between pockets 54, also 55 (Fig. 3). Any number of plungers may be operated simultaneously in any cavity, 29, 38, 39, and the several cavities may be operated in staggered time relation to render the flow through the motor 36 less irregular.

When tickets are sold continuously throughout a considerable period of time and it is desired to register the totalized sales at successive intervals in that period, a desired registration may be taken without stopping the continuity of sales. There are provided in all ducts between the ball emitters and the ball counters stop gates, preferably under control of a clock contact.

Referring to Figure 2: a stop gate 155 is pro-

vided for each duct upon a shaft 156. Clock 161 closes a contact and energizes magnet 160 which by armature 159 operates latch 158 to release shaft 156 which moves all gates 155 to stop all balls. Balls which had not passed the gate are held stored in the ducts, and all balls which had passed the gate pass quickly through the counters and operate the registers, which then stop all movement of dials. A contact 164 closed by shaft 156 energizes a signal device 164 to attract attention of an attendant. The attendant registers manually by means not shown the readings of all ball-operated registers, then operates the handle, 162, to restore all gates 155 thus releasing all stored balls into the counters, rendering the entire system operative pending closure of the next clock contact.

When a race has started, it is desired to stop all ticket sales and to effect this control from a single point. For this purpose equipment already described is largely used. An electrical switch 255 (Fig. 1), controls a multicontact relay 226 over an obvious circuit. Relay 226 when operated connects ground to all conductors, as 175, 183, 186, 212, and others, thus energizing all substation magnets, as 176, 213, and others, and locking all ticket issuing slides, as slide 85 (Figs. 6 and 7) locked by energization of magnet 90.

While the invention has been described by illustration of a single embodiment thereof, the true scope of the invention is limited only by the appended claims.

What I claim is:

1. In a ticket issuing machine for stacked tickets and having a discharge opening through which a ticket may be issued, a ticket shifting member manually movable to shift a ticket initially toward said discharge opening, an electromagnet, an armature member therefor, first cooperating stops on said members engageable to restrain said ticket shifting member from effective movement when said armature member is in operated position, second cooperating stops on said members engageable to restrain said ticket shifting member at a mean position when said armature member is in unoperated position, remote controlling means for energizing said magnet to render said armature member effective to disengage said second cooperative stops to permit further movement of said ticket shifting member, to shift farther said shifted ticket, and follower means engageable by said further shifted ticket and effective automatically to issue said ticket completely.

2. In a ticket issuing machine for stacked tickets and having a discharge opening through which a ticket may be issued, a ticket shifting member manually movable to advance a ticket initially toward said discharge opening, an electromagnet, an armature member therefor, cooperating stops on said members engageable to restrain said ticket shifting member at a mean position when said armature member is in unoperated position, remote controlling means for energizing said magnet to render said armature member effective to disengage said stops to permit further movement of said ticket shifting member, to shift farther said shifted ticket, and follower means engageable by said further shifted ticket and effective automatically to issue said ticket completely.

3. In a ticket issuing machine for stacked tickets and having a discharge opening through which a ticket may be issued, a ticket shifting member manually movable for shifting a ticket

toward said discharge opening, an electromagnet, an armature member therefor, first cooperating stops on said members engageable to restrain said ticket shifting member at its normal position when said armature member is in its operated position, second cooperating stops on said members engageable to restrain said ticket shifting member at a mean position when said armature member is in unoperated position, electrical contacts closable by said ticket shifting member when in said mean position and said second cooperating stops are in engagement, remotely located controlling means, electric circuits connecting said ticket issuing machine and said remote controlling means, said controlling means responsive to said contacts over one of said electrical circuits and effective over another of said circuits for energizing said electromagnet to operate said armature member to disengage said second stops and to release said ticket shifting member to shift said ticket further, and follower means engageable by said further shift ticket for automatically issuing said ticket completely.

4. In a ticket issuing machine for stacked tickets and having a discharge opening through which a ticket may be issued, a ticket shifting member manually movable for shifting a ticket toward said discharge opening, an electromagnet, an armature member therefor, cooperating stops on said members engageable to restrain said ticket shifting member at a mean position when said armature member is in unoperated position, electrical contacts closable by said ticket shifting member when in said mean position and said stops are in engagement, remotely located controlling means, electric circuits connecting said ticket issuing machine and said remote controlling means, said controlling means responsive to said contacts over one of said electrical circuits and effective over another of said circuits for energizing said electromagnet to operate said armature member to disengage said stops and to release said ticket shifting member to advance said ticket further, and follower means engageable by said further advanced ticket for automatically issuing said ticket completely.

5. In a ticket issuing machine for stacked tickets and having a discharge opening through which a ticket may be issued, a ticket shifting member manually movable to shift a ticket toward said discharge opening, follower means for completely issuing a shifted ticket, a ticket detector member, an electrical contact operable by said ticket detector member under control of a shifted ticket in process of issuance by said follower means, a remotely located ball emitter, an electric circuit connecting said ticket issuing machine and said ball emitter, and means in said ball emitter to emit a ball responsive to operation of said electrical contact incidental to complete issuance of a ticket.

6. In a ticket issuing machine for stacked tickets and having a discharge opening through which tickets may be issued, a ticket shifting member manually movable to shift a ticket toward said discharge opening, a first electrical contact operated by said ticket shifting member in moved position, an electromagnet, an armature member therefor, cooperating stops on said members engageable to restrain said ticket shifting member at a mean position when said armature is in unoperated position, a remotely located ball emitter, electric circuits connecting said ticket issuing machine and said ball emit-

ter, a second electric contact in said ball emitter closable by a ball in position for emission, and means in said ball emitter responsive to operation of said first electrical contact over one of said circuits and through said second contact and effective over another of said circuits to energize said electromagnet to render said armature member effective to disengage said stops to permit further movement of said ticket shifting member.

7. In a ticket issuing machine for stacked tickets and having a discharge opening through which tickets may be issued, a ticket shifting member manually movable to shift a ticket toward said discharge opening, mechanical locking means and electrically operable unlocking means for said member in moved position, a first electrical contact operated by said ticket shifting member in moved position, a remotely located ball emitter, electric circuits connecting said ticket issuing machine and said ball emitter, a second electrical contact in said ball emitter closable by a ball in position for emission, means in said ball emitter responsive to operation of said first electrical contact over one of said circuits and through said second contact and effective over another of said circuits to energize said electrically operable unlocking means to permit further movement of said ticket shifting member, and means in said ball emitter to emit said ball responsive to control over one of said circuits by said ticket detector contact.

8. In a ticket issuing machine for stacked tickets and having a discharge opening through which tickets may be issued, shifting means to shift a ticket initially and to shift said shifted ticket farther toward said discharge opening, follower means for shifting said shifted ticket still farther for completing issuance of said ticket, a first electrical contact closed by said shifting means when said ticket is in initially shifted position, a ticket detector member, a further electrical contact closed by said ticket detector member when said ticket is shifted farther by said follower means, an electromagnetically controlled lock for said shifting means in initially-shifted-ticket position, a remotely located circuit controller, circuits connecting said ticket issuing machine and said circuit controller, means in said circuit controller responsive over one of said circuits to operation of said first contact and effective by current over another of said circuits to energize said electromagnetically controlled lock to unlock said shifting means to permit said shifting means to shift said ticket farther into said follower means, and means in said circuit controller responsive to current incident to operation of said further electrical contact and effective to interrupt said current and to de-energize said lock.

9. In a ticket issuing system, a ticket issuing machine for stacked tickets and having a discharge opening through which a ticket may be issued, a remotely located ball emitter, circuits connecting said ticket issuing machine and said ball emitter, a resistor at said ticket issuing machine, means to shift a ticket toward said discharge opening and incident thereto to close one of said circuits through said resistor, means in said ball emitter conditioned by a ball in condition for emission and responsive to current in said closed one of said circuits and effective to close a further one of said circuits, means in said ticket issuing machine for further shifting said ticket and for issuing said ticket completely

and incident thereto to close said first mentioned one of said circuits excluding said resistor for increased current, and means in said ball emitter to emit said ball responsively to said increased current.

10. In a ticket issuing system, a ticket issuing machine, a ball emitting machine, circuits connecting said ticket issuing machine and said ball emitting machine, ticket controlled contacts in said ticket issuing machine, ball controlled contacts in said ball emitting machine, ticket issuing means in said ticket issuing machine effec-

tive to issue a ticket and conditioned for operation by current over one of said circuits incident to closure of said ball controlled contacts in said ball emitting machine under control of a ball in position for emission, and ball emitting means in said ball emitting machine effective to emit a ball and conditioned for operation by current over one of said circuits incident to closure of said ticket controlled contacts in said ticket issuing machine under control of a ticket in position for issuance.

CLYDE SMITH.
